CLYDE A. COOK, OF PATERSON, NEW JERSEY

AUTOMATIC WARP BEAM ADJUSTMENT

Application filed July 7, 1930. Serial No. 466,212.

It is desirable in the operation of looms, to maintain the warp ends at a predetermined level and, in accordance with this invention, this result is effected automatically by elevating the warp beam to compensate for its reduction in diameter as the warp is drawn therefrom, thereby preserving the level of the warp ends throughout the weaving operation.

10 The invention contemplates an adjustable mounting for the warp beam, mechanism deriving power from a moving part of the loom to automatically elevate the warp beam mounting, and an automatic control for 15 throwing the elevating mechanism into and out of gear as the warp beam rises and its diameter diminishes, whereby to maintain the level of the warp ends.

While the drawings illustrate a preferred 20 embodiment of the invention, it is to be understood that in adapting the means to meet specific needs and requirements, the design may be varied and changes in the minor details of construction may be resorted to within 25 the scope of the invention as claimed, without departing from the spirit thereof.

For a full understanding of the invention and the merits thereof, reference is to be had 30 to the following description and the drawings hereto attached, in which:

Figure 1 is an end view of a conventional 35 form of loom, showing more clearly the warp beam and mechanism associated therewith for automatically elevating the beam to maintain the warp ends at a predetermined level.

Figure 2 is a fragmentary view in side elevation.

Figure 3 is a fragmentary sectional view 40 on the line 3—3 of Figure 1, looking to the right as designated by the arrows.

Figure 4 is a detail sectional view on the line 4—4 of Figure 3.

Figure 5 is an enlarged fragmentary sec- 45 tional view on the line 5—5 of Figure 2.

Figure 6 is an enlarged detail sectional view on the line 6—6 of Figure 2.

Figure 7 is an enlarged detail sectional view on the line 7—7 of Figure 6, looking to the left as indicated by the arrows, showing 50 the ratchet mechanism for imparting an intermittent rotary movement to the elevating mechanism.

Figure 8 is a detail side view of a portion 55 of the loom, the mounting for the warp beam and the automatic control for throwing the elevating mechanism into and out of gear.

Figure 9 is an enlarged perspective view of 60 the warp beam mounting, the guide therefor, and the brackets for the warp beam control.

Corresponding and like parts are referred to in the following description and designated in the several views of the drawings by like reference characters.

Side members of the loom frame 1 are provided with ribs 2 which constitute guides for the warp beam mounting. This mounting comprises a pair of elevators or jacks 3 formed in a side with a groove or channel 4 to snugly receive the guide ribs 2. The sides of 65 the ribs 2 are undercut to receive overhanging portions of the elevator or jack 3 bordering upon the groove or channel 4. In this manner, the elevators or jacks 3 are retained in place and directed in their vertical move- 70

ment. Transverse grooves 5 are formed in the upper ends of the elevators 3 and receive the journals of the warp beam 6. Elevating or jack screws 7 engage the elevators 3, as 75 shown most clearly in Figure 1 of the drawings, to effect a vertical movement thereof to elevate the warp beam 6 as the warp threads are drawn therefrom, to maintain the warp ends at the predetermined level. The lower ends of the elevating screws 7 engage worm 80 gears 8 disposed in boxes 9 secured to the floor. Covers 10 close the gear boxes 9. A transverse shaft 11 is mounted in the gear boxes 9 and receives a worm 12 adjacent each 85 end and which is confined between the boxes 90

9 and their covers 10. Rotation of the shaft 11 effects a corresponding rotary movement of the elevating screws 7 through the instrumentality of the worm gearing 8 and 12. The 5 lower ends of the elevating screws 7 are tapered and stepped in the boxes 9, as shown most clearly in Figure 7 of the drawings. That portion of the elevating screws 7 engaging the worm gears 8 is square, as indicated most clearly in Figure 6 of the drawings. 10 The construction is such as to admit of lifting the elevating screws 7 to clear the worm gears 8 and boxes 9 so that the elevators or jacks 3 may be independently adjusted 15 when placing warp threads upon the warp beam.

A ratchet wheel 13 is mounted upon the shaft 11 and a dog 14 coacts therewith to impart an intermittent rotary movement to the 20 shaft 11 and the elevating screws 7. A rod 15 is forked at one end and carries the dog 14 which is pivoted thereto between the fork members, as indicated most clearly in Figure 5 of the drawings. The ratchet wheel 13 25 is likewise disposed between the members of the fork. A forked upright 16 is pivoted at its lower end and the rod 15 is adjustably connected to one of the fork members. A rod 17 is adjustably connected to the other fork 30 member of the upright 16. One of the fork members of the rod 15 is extended and adjustably connected to a pivoted upright 18. The rod 17 is connected to an eccentric 19 fitted to the usual crank or cam shaft 20 of the 35 loom. The cam 19 is split and formed with a clamp 21 which admits of fitting it to the shaft 20. The loom is operated by means of power applied to the shaft 20 and through the eccentric 19 the rod 17 is reciprocated and 40 imparts a corresponding movement to the rod 15 and the dog 14 pivoted thereto. This results in imparting an intermittent rotary movement to the shaft 11 and the elevating screws 7, whereby the elevators 3 and warp beam 6 45 are adjusted vertically to maintain the level of the warp ends.

Contact between the dog 14 and ratchet wheel 13 is automatically controlled by means of the warp beam. A control lever 22 is pivoted upon a rod 23 projecting inwardly from a bracket 24 attached to the loom frame 1. The control lever 22 carries a roller 25 which engages the top portion of the warp beam 6. A stout wire or light rod 26 forms connecting 50 means between the control lever 22 and the dog 14. The connection 26 passes loosely through the lever 22 and receives a nut 27 and spring 28, the latter being interposed between the lever and nut. Adjustment of 55 the nut 27 determines the contact between the dog 14 and the ratchet wheel 13. As shown most clearly in Figure 1 of the drawings, the roller 25 engages and rests upon the warp threads adjacent the end of the 60 warp beam 6 and as the diameter decreases

by withdrawal of the warp threads from the warp beam, the roller 25 lowers and, in consequence, the connection 26 moves downward and permits the dog 14 to engage the teeth of the ratchet wheel 13 and impart an intermittent rotary movement to the shaft 11 and elevating screws 7 geared thereto. This results in a lifting of the jacks 3 and warp beam 6 to bring the warp ends to the predetermined level, with the result that the control lever 22 is moved upward and effects disengagement of the dog 14 from the ratchet wheel 13. This operation is automatic and when the level of the warp ends lowers, the elevating mechanism automatically operates to lift the warp beam and bring the warp ends to the predetermined level. 75 80

Each of the elevators or jacks 3 is provided with wings 29 and 30 to which brackets 31 and 32 are attached. The brackets 31 extend inwardly and downwardly and terminate in horizontal extensions 33 which are slotted to receive the lower ends of cords 34 which are wound around pulleys 35 fast to the ends of the warp beam 6. The lower ends of the cords 34 are knotted to prevent withdrawal through the slots of the extensions 33. Weights 36 may be placed upon the horizontal extensions 33. A lever 37 is pivoted at one end to each of the brackets 31 and 32 and receives weights 38 at its opposite end. A cord 39 is attached at one end to each of the levers 37 and its opposite end portion passes around the pulley 35 in a reverse direction to the cord 34. For a dead weight, 90 the lower ends of the cords 34 are knotted and slipped into the slots of the horizontal extensions 33 with the knots therebelow to prevent upward disengagement of the cords from the extensions. When balanced 95 weights 36 are employed, the cords are engaged therewith and the weights rest upon the horizontal extensions 33. The bracket 32 provides for the use of lever weights. It is observed that the weighting system for the 100 warp beam is carried by the elevators or jacks 3, thereby moving with the warp beam mounting and preventing imperfections in the weaving. 105 110

It is observed that the level of the warp ends is maintained automatically without any attention on the part of the loom fixer. The construction also admits of either one of the jacks 3 being independently adjusted as occasion may require. The elevating mechanism is automatically controlled from the warp beam and is thrown out of action when the warp ends occupy the predetermined level and is automatically thrown into action when the level of the warp ends lowers, this being effected by the control levers 120 125 130 22 in the manner stated.

What is claimed is:

1. In a loom, the combination with the warp beam, of means actuated from a mov-

- ing part of the loom and controlled from the warp beam for automatically elevating the warp beam to maintain the warp ends at a predetermined level.
5. In a loom, the combination with the warp beam, and a mounting therefor comprising independent jacks, of means for adjusting the jacks separately, and means actuated from a moving part of the loom and controlled from the warp beam for simultaneously adjusting both of the jacks to elevate the warp beam to maintain the warp ends at a given level.
10. In a loom, the combination with the warp beam and a mounting therefor comprising independent jacks, interfitting guide means between the jacks and loom frame holding the jacks to a rectilinear path in their vertical movement, and means actuated from a moving part of the loom and controlled from the warp beam to adjust the jacks and elevate the warp beam to maintain the warp ends at a predetermined level.
15. In a loom, the combination with the warp beam and a mounting therefor adjustable vertically, of operating means actuated from a moving part of the loom to effect automatic adjustment of the warp beam mounting to maintain the warp ends at a given level, said operating means including a ratchet mechanism controlled from the warp beam for intermittent actuation of the operating mechanism.
20. In a loom, the combination with the warp beam and a mounting therefor adjustable vertically, of operating means for effecting automatic vertical adjustment of the warp beam mounting, the same including power transmitting rods adjustably connected and actuated from a moving part of the loom, and a ratchet mechanism connected with said rods and controlled from the warp beam for effecting vertical adjustment of the mounting by intermittent stages.
25. In a loom, the combination with the warp beam and a mounting therefor adjustable vertically, of operating means adapted to be actuated from a moving part of the loom to effect automatic adjustment of the warp beam mounting, said operating mechanism including separable parts, and control means actuated from the warp beam to automatically throw said separable parts into and out of engagement.
30. In a loom, the combination with the warp beam and adjustable mounting therefor movable vertically, of operating means for effecting automatic adjustment of the warp beam mounting, and control means actuated from the warp beam for automatically throwing said operating mechanism into and out of action.
35. In a loom, the combination with the warp beam, a mounting therefor adjustable vertically, and operating means for effecting automatic adjustment of the warp beam mounting including a ratchet and dog, of a control member actuated from the warp beam, and a yieldable connection between the control member and the said dog.
40. In a loom, the combination with the warp beam, a mounting therefor adjustable vertically, and operating means for effecting automatic adjustment of the mounting including a ratchet and dog, a control member adapted to be actuated from the warp beam, a connection between said control member and dog, an adjustable stop on said connection, and a spring between the adjustable stop and the control member.
45. In a loom, the combination with the warp beam and a mounting therefor adjustable vertically, of operating means actuated from a moving part of the loom to effect automatic adjustment of the warp beam mounting including a ratchet and dog, of a control lever supported by the warp beam and actuated thereby, and an adjustable and yieldable connection between the control lever and said dog.
50. In a loom, the combination with the warp beam mounted for vertical adjustment, of operating means actuated from a moving part of the loom for effecting automatic adjustment of said beam, and control means actuated from the warp beam for automatically throwing the adjusting mechanism into and out of gear.
55. In a loom, the combination of the warp beam, a mounting therefor including separate jacks receiving the journals of the warp beam at their upper ends, elevating screws in threaded engagement with said jacks, a transverse shaft, gearing between said shaft and the elevating screws, the screws being detachable from said gearing to admit of independent adjustment of the jacks, and means actuated from a moving part of the loom controlled from the warp beam to impart an intermittent rotary movement to the said shaft and elevating screws.
60. In a loom, the combination of the warp beam, vertically adjustable jacks therefor, elevating screws for the jacks, gear boxes having the elevating screws stepped therein, worm gears in said boxes and having the elevating screws detachably engaged therewith, a transverse shaft mounted in the gear boxes, worms on said shaft and in mesh with the worm gears, top plates closing the gear boxes and retaining the shaft and worms in place, and operating means actuated from a moving part of the loom and controlled from the warp beam for imparting an intermittent rotary movement to the said transverse shaft.
65. In a loom, the combination of the warp beam, elevating jacks therefor, adjusting screws for the jacks, a transverse shaft, gearing between the transverse shaft and adjusting screws, operating means for imparting an intermittent rotary movement to the

transverse shaft from a moving part of the loom and including a ratchet wheel and co-acting dog, a control lever in contact with the warp beam and actuated thereby, adjustable and yieldable connecting means between the control lever and dog, and tensioning means for the warp beam mounted upon the elevating jacks and adjustable therewith and with the warp beam to insure the weaving of a cloth free from imperfections.

10 In testimony whereof I affix my signature.
